UNITED STATES PATENT OFFICE.

GEORGE V. STRAHAN, OF NEWARK, NEW JERSEY, ASSIGNOR TO MITCHELL VANCE CO., INC., OF NEW YORK, N. Y., A CORPORATION OF NEW YORK.

DESIGN FOR A CHANDELIER-ARM FOR A LIGHTING-FIXTURE.

56,776.

Specification for Design.

Patented Dec. 14, 1920.

Application filed June 30, 1920. Serial No. 393,175. Term of patent 7 years.

To all whom it may concern:

Be it known that I, GEORGE V. STRAHAN, a citizen of the United States of America, residing in the city of Newark, county of Essex, and State of New Jersey, have invented a new, original, and ornamental Design for a Chandelier-Arm for a Lighting-Fixture, of which the following is a specification, reference being had to the accompanying drawings, forming part thereof.

Figures 1 and 2 of the accompanying drawings are respectively plan and cross-sectional views of a chandelier arm for a lighting fixture, showing my new design.

I claim:

The ornamental design for a chandelier arm for a lighting fixture, as shown.

GEORGE V. STRAHAN.
